STILLMAN W. MCKEE AND JAMES H. ALLEN, OF LOS ANGELES, CALIFORNIA; SAID ALLEN ASSIGNOR TO SAID MCKEE.

SHELF WITH LABEL.

1,402,877.

Specification of Letters Patent. Patented Jan. 10, 1922.

Application filed October 18, 1920. Serial No. 417,737.

To all whom it may concern:

Be it known that we, STILLMAN W. MCKEE and JAMES H. ALLEN, citizens of the United States, and residents of Los Angeles, county 5 of Los Angeles, State of California, have invented a new and useful Shelf with Label, of which the following is a specification.

This invention relates to a shelf provided with a label to designate the character of the 10 objects on the shelf. It is especially useful in libraries or other places where it is desired to indicate the character of the contents of the volumes on the shelf by a suitable label mounted conveniently on the front edge of 15 the shelf. Heretofore labels have been applied in some manner to the edges of the shelves for the purpose mentioned above, but by the old construction, as the volumes on the shelf were re-arranged to accommodate additional 20 volumes on the same subjects, it was necessary in many instances to entirely remove the label and substitute therefor another label. It has been heretofore proposed to groove the edge of the shelf and insert the 25 label in the groove and with such construction, when it is desired to change the position of the label lengthwise of the shelf, the label is simply moved along the groove to the new position. With such construction the 30 lower edge of the label rests upon the bottom of the groove and consequently any dirt, paint or other material that may obstruct the groove forms an obstruction which makes it difficult to move the label along the groove. 35 This invention provides a label which can be readily moved along the shelf, the construction being such that the edges of the label do not contact with the bottom of the groove, thus avoiding the difficulty noted 40 above.

Several different forms of the invention are provided, but the fundamental feature characterizing all of them is the flanged construction of the slide and beads on the edge 45 of the shelf adapted to engage the flange to hold the label in place.

The accompanying drawings illustrate the invention:

Figure 1 is a perspective view of a book- 50 case provided with shelves constructed in accordance with the provisions of this invention.

Fig. 2 is an enlarged fragmentary front

elevation of one of the shelves showing one of the labels in place.

Fig. 3 is a sectional elevation on line X³—X³, Fig. 2.

Fig. 4 is a fragmental front elevation, analogous to Fig. 2, of a modified form of the invention.

Fig. 5 is a sectional elevation on line indicated by X⁵—X⁵, Fig. 4.

Fig. 6 is a sectional elevation similar to Figs. 3 and 5 showing a still different modification of the invention.

The shelves are indicated at 1 and are supported in any suitable manner on the standards *a* or other suitable structure. The shelves are of like construction and therefore but one of them needs to be described. The 70 shelf 1 is provided with a groove 2 extending lengthwise in its front edge, and at least a portion of the groove has an undercut portion, as indicated at 3 in Figs. 3 and 5 and at 4 in Fig. 6.

Now referring more particularly to Figs. 3 and 5, the undercut portions 3 of the groove define wedge-shape beads 5, the narrower portions of the beads being adjacent one another but spaced slightly apart. The groove 80 2 may be formed by sawing from the corners of the front edge inwardly at an angle so that the saw cuts cross one another, thus making the outer faces of the beads extend aslant inwardly toward each other. The 85 dotted line *b* in Figs. 3 and 5 indicates how the material may be cut away to deepen the groove when such construction is desired. The advantages of the deeper groove will be 90 set forth hereinafter.

Now referring more particularly to Fig. 6 of the drawings the undercut portions 4 are spaced apart so as to leave a rib 6 therebetween, said rib being provided with wedge-shape beads 7 which are similar to the beads 95 5 excepting that the narrower portions are turned away from one another.

From the foregoing it is clear that the groove may be variously constructed, but it is to be noted that a feature of the grooves common to the different forms of the invention is the wedge-shaped beads, and it is these beads which serve to retain the slide that is indicated at 8 and is constructed as follows:

The slide comprises a flat member 9 and 100 rearwardly converging flanges 10. In Figs.

3 and 5 the rear faces of the flanges 10 rest against the front faces of the beads 5, and in Fig. 6 the front faces of the flanges rest against the rear faces of the beads 7. From 5 this it is clear that in the form of the invention shown in Fig. 6 the flanges 10 are sufficient of themselves to shiftably support the slide on the edge of the shelf.

In Figs. 3 and 5 to the flanges 10 are 10 joined rearwardly divergent flanges 11, the front faces of which engage the rear faces of the beads 5 in the same manner that the flanges 10 engage the rear faces of the beads 7 in the form of the invention shown in Fig. 15 6. Thus in Figs. 3 and 5 the flanges 11, though the reverse of the flanges 10 in Fig. 6, serve to shiftably support the slide on the edge of the shelf. The flange 10 in Fig. 6 and flanges 11 in Figs. 3 and 5 are of less 20 width than the undercut portions of the grooves 2, so as not to engage the bottom of the undercut portions, in consequence of which if there be any dirt or paint or other obstruction in the bottom of the groove such 25 obstruction will not prove to be an obstacle to the shifting of the slide lengthwise of the shelf. The flanges 10 in Fig. 6 and the flanges 10, 11 in Figs. 3 and 5 form a contracted portion of the slide.

30 The slide may be made of any suitable material, it being preferable that the material be of a more or less resilient character or that at least the flanges 10 in Fig. 6 and the flanges 11 in Figs. 3 and 5 be more or 35 less resilient. The slide 8, for example, may be made of paper, cardboard or sheet metal. In Fig. 2 the slide is illustrated as being provided with a legend or inscription 12 and such legend may be written, printed or 40 stamped upon the slide, which thus constitutes the label. The legend indicates the character of the works placed on the shelf contiguous to the slide, that is to say above or below the shelf according to the desires 45 of the librarian. In Fig. 1 the slides are positioned on the shelf supporting the works designated by the different legends on the slides. If desired the legend may be written, printed or stamped upon a slip 13 positioned against the rear face of the slide 50 as in Figs. 5 and 6. In this instance the slip constitutes the label. When the slip 13 is employed, if the slide is formed of opaque material, the slide may be provided with an 55 opening 14 as in Fig. 4, through which opening the legend 15 of the slip may be viewed; or, if desired, the slide may be formed in whole or in part of transparent material such as celluloid or the like, and 60 in that event the opening 14 will not be necessary and may be omitted.

From the foregoing it is clear that any suitable material may be employed for the slide 8, provided only that, if the legend is

to appear on a slip instead of on the slide, 65 the member 9 will either be provided with an opening or at least a portion of the member 9 will be transparent so that the legend may be observed.

The slides may be inserted in the grooves 70 2 before the shelf is installed in position on the supporting structure, or said slides may be readily snapped into place by first inserting one of the flanges 10 in Fig. 6 or 11 in Figs. 3 and 5 into the groove and then 75 springing the other flange into the undercut portion of the groove. A suitable tool may be devised to aid in springing the slide into the groove if said slide be made of stiff material such as sheet metal. If it be desired 80 to remove the slide from the shelf so as to change the legend, the slide will be forced outwardly by inserting the finger beneath one end thereof or a suitable tool may be inserted in the groove beneath the slide to pry 85 the slide out of the groove, the flanges yielding sufficiently to permit of this. In order to permit of the ready insertion of the tool beneath the slide it may be preferable to cut the groove to the broken line indicated at b in Figs. 3 and 5 as hereinbefore 90 described.

To make the insertion of the slides in the groove as easy as possible, it may be desirable to cut an opening through the beads 95 and such opening is shown at 16 in Fig. 2. The opening 16 readily permits the flanges 10 of the form shown in Fig. 6 or the flanges 11 of the forms shown in Figs. 3 and 5 to be inserted into the groove through said 100 opening.

From the foregoing it will be readily understood that if it be desired to place additional volumes upon the shelf pertaining to any given subject, the slides may be appropriately shifted along the shelf to position 105 them correctly with respect to the volumes to which the legends refer.

The invention is of comparatively simple construction and when the shelves are made 110 as described the labels can be very readily attached to the shelves, such attaching not requiring any special skill. It will also be clear that the labels can be placed in position and changed from one position to 115 another in a comparatively short space of time.

We claim:

1. In combination, a shelf having a groove in its front edge defining faces extending 120 aslant inwardly toward each other and defining wedge-shape beads, and a slide having portions engaging the undercut portions of the groove and having a flat face in front of said engaging portions of less 125 width than the groove, and said flat face lying within the groove.
2. In combination, a shelf having a groove

provided with undercut portions, the groove first flanges and engaging the rear faces of 10 defining wedge-shape beads having their outer faces extending aslant inwardly toward each other, the narrower portions of 5 the beads being adjacent one another but spaced slightly apart, and a slide having rearwardly converging flanges resting against the front faces of the beads, the slide having rearwardly divergent flanges joined to the

first flanges and engaging the rear faces of 10 the beads.

Signed at Los Angeles, California, this 12th day of October, 1920.
